J. Byrnes, Townsend & Bickerton,
Attorneys.

UNITED STATES PATENT OFFICE.

PIERRE E. HAYNES, OF BUFFALO, NEW YORK, ASSIGNOR TO THE LINDE AIR PRODUCTS COMPANY, A CORPORATION OF OHIO.

APPARATUS FOR TRANSPORTING GASES.

Application filed March 11, 1922. Serial No. 543,060.

To all whom it may concern:

Be it known that I, PIERRE E. HAYNES, a citizen of the United States, residing at Buffalo, in the county of Erie and State of New York, have invented certain new and useful Improvements in Apparatus for Transporting Gases, of which the following is a specification.

This invention relates to portable glass apparatus adapted for the transportation of gases from place to place, the apparatus of the invention being especially adapted for use in connection with gases, for example neon, which because of their scarcity and consequent high price, require the exercise of extraordinary precautions to prevent loss and contamination.

The invention includes a novel type of valve which is to a high degree proof against breakage and accidental displacement, and includes also an improved form of terminal connection whereby the apparatus may be quickly and securely attached to the gas-producing or gas-using apparatus. A specific embodiment of the invention will be described in connection with the annexed drawing, in which the figure shows an elevation partly in longitudinal section of an apparatus in accordance with my invention.

In the drawing, 1 represents the gas container proper. To the container is integrally attached the neck 2, which serves as a filling and discharging conduit for the container. Integrally attached to the conduit 2 at the end remote from the container 1 is an accurately ground valve seat 3 which lies within the conduit and the axis of which coincides with that of the conduit. Cooperating with the valve seat 3 is a conical valve head 4 ground to an accurate fit with valve seat 3. An orifice 5 in the seat and an orifice 6 in the head are so located that in one position of the parts these orifices are brought into register, thereby forming a gas conduit connecting the interior and exterior of the container. The valve head 4 carries an integral enlarged portion 7 accurately ground to a regular surface 8.

That portion of the apparatus which has thus far been described is portable and designed to be shipped back and forth between the place where the gas is produced and the place where it is used. Either the gas-pro-

ducing or the gas-using apparatus, preferably both, are provided with a conduit 9 having an integral enlarged portion 10 which has the accurately ground regular surface 11 conforming exactly to the ground surface 8 of the part 7. Because of the facility with which a plane surface can be formed or reproduced, the surfaces 8 and 11 are preferably plane surfaces, though surfaces of other forms, for example conical, spherical or cylindrical, might be used, the only essential requirement being that the surfaces on the parts to be fitted together shall be in contact at all points to prevent gas leakage. Part 7 has in its ground surface an orifice 12 while the part 10 has a corresponding orifice 13, these orifices being so placed that they coincide when the ground surfaces are brought together. With the valve in open position, there is then a free gas passage connecting the interior of the container 1 to the gas-producing or the gas-using apparatus.

The conduit 2 carries adjacent the valve seat projecting hooks 14, and similar projecting hooks 15 are provided on the valve head 4. Rubber-bands 16, suitably arranged on these cooperating hooks, serve to prevent any undesired relative movement, either rotary or longitudinal, between the valve surfaces and insure that the valve will not become accidentally opened or displaced in such manner as to permit leakage. The parts 7 and 10 are likewise provided with projecting hooks 17 and 18 and rubber-bands or the like 19 secured to these hooks, which serve a similar purpose and prevent leakage at the juncture of the ground surfaces 8 and 11.

The method of using the apparatus is as follows: Upon return of the apparatus to the gas-producing station, the valve composed of parts 3-4 will be closed, the container 1 will contain some residual rare gas at a pressure considerably below atmospheric, and the valve head 4 will be filled with air at atmospheric pressure. The apparatus is placed with its ground surface 8 against the ground surface 11 of the gas-producing apparatus, and the rubber-bands 19 are applied to hold these parts securely in contact. The air is then evacuated from the valve head 4, the valve remaining closed. The valve is turned to open position

and secured in this position by the rubber bands 16. If there is any reason to suspect that the residual gas in the container is contaminated, or if the container is to be refilled with a different gas, the evacuation is continued after opening the valve. The apparatus is then in condition for filling and gas is introduced until a pressure slightly below atmospheric pressure prevails in the interior of the container. Without disconnecting the apparatus from the gas-producing apparatus, the valve is then turned to its closed position and secured in this position by the bands 16. The bands 19 are then removed, the ground surfaces 8 and 11 are separated and the container is charged and ready for shipment.

Upon arriving at the place where the gas is to be used the operations are reversed, a secure joint being first made between the surfaces 8 and 11, the air which has entered the valve head 4 during shipment being evacuated and the valve then turned to its open position, both the ground glass joints being secured by rubber bands as before. The receptacle is then in condition for discharge, the gas being pumped out of it until the residual gas is at very low pressure. The stop-cock is then closed and secured in its closed position, the joint broken between surfaces 8 and 11 and the apparatus returned to the gas-producing station.

It will be understood that since gases of the kind mentioned are usually used at pressures much below barometric, the interior of a receptacle used for transporting such gases will be at reduced pressure at practically all times. This fact renders rubber tubing unsuitable for making connections, and all joints are usually welded by fusion. With an apparatus according to my inven-

tion, the necessity for all temporary welded joints is entirely obviated.

The specific embodiment of the invention described above is subject to many modifications, and the scope of the invention is limited only by the appended claims. 45

I claim:

1. In combination, a portable glass apparatus comprising a container for gases, a valve-controlled filling and discharging conduit attached to said container, the terminus of said conduit being ground to a regular surface, and a second glass conduit adapted to be connected to a gas-producing or gas-using apparatus, said second conduit having a terminus ground to fit the terminus of the conduit attached to the container. 55

2. The invention according to claim 1 in which the termini of the conduits are provided with projections adapted to receive elastic holding members. 60

3. A portable glass apparatus comprising a container for gases, a perforated conical valve seat integrally attached to said container and a perforated conical valve head fitted to said seat, the axes of said valve seat and valve head substantially coinciding with the axis of said container. 65

4. A portable glass apparatus comprising a container for gases, a filling and discharging conduit integrally attached thereto, a conical valve seat integral with said conduit, the axes of the valve seat and the conduit being coincident, and a valve head co-operating with said valve seat. 70

5. Apparatus according to claim 4 in which the valve seat and valve head are held against undesired relative movement by elastic means. 75

In testimony whereof, I affix my signature. 80

PIERRE E. HAYNES.
